UNITED STATES PATENT OFFICE

BRUNO RADTKE, OF LIBERTYVILLE, ILLINOIS, ASSIGNOR TO MILLS NOVELTY COMPANY, OF CHICAGO, ILLINOIS, A CORPORATION OF ILLINOIS

COIN MECHANISM

Application filed February 16, 1931. Serial No. 516,056.

This invention relates to an improved type of coin control mechanism adapted for use in connection with various types of coin-operated instruments such as vending machines, 6 amusement devices, and the like.

An important object of the invention is to provide in a coin mechanism of the class referred to an improved slug detecting mechanism which will positively prevent operation 10 of the controlled machine with iron checks or other magnetic slugs.

Another object of the invention is to provide a coin mechanism of this character having improved means for testing the quality of 25 the coin as to size and shape in such a manner as to positively eliminate the possibility of obtaining operation of the controlled machine by the use of perforated coins or coins which are either too large or too small.

20 Other objects and advantages of the invention will be apparent from the following description, which, taken in connection with the accompanying drawings, discloses a preferred embodiment thereof.

25 Referring to the drawings:

Fig. 1 is a front elevational view of a vending machine provided with coin control mechanism embodying my invention;

Fig. 2 is a detail sectional and elevational 30 view of the coin mechanism being taken on the line 2-2 of Fig. 1;

Fig. 3 is a rear view of the mechanism taken as indicated by the line 3-3 of Fig. 2;

Fig. 4 is a front view of the same taken on 35 the line 4-4 of Fig. 2;

Fig. 5 is a view similar to Fig. 4 and showing the parts in a different operative position;

Fig. 6 is a horizontal section through the coin mechanism taken on the line 6-6 of Fig. 40 4; and

Fig. 7 is a detail section showing the mechanism for detecting perforated coins, the section being taken on the line 7-7 of Fig. 6.

In the embodiment selected for illustration 45 in the drawings, I have shown the coin control mechanism is connected with a machine for vending packages of candy, such as mints and the like. The machine is housed in a box-shaped casing consisting of a back wall 11, a top wall 12, a bottom wall 13, side walls

14, and a front cover plate 15 which is hinged-
ly connected at its lower front edge to the
bottom wall 13. The cover plate 15 is nor-
mally held in closed position on the casing
by a lock 16. A discharge port 17 is provided 55
in the cover plate 15 and is positioned to reg-
ister with a suitable discharge chute posi-
tioned on the interior of the casing to provide
means for delivery of the packages to the op-
erator. The vending mechanism which is en- 60
closed within the casing, may be of any suit-
able form and is not shown in the drawings
since it does not form a part of the present
invention.

Referring to Figs. 2 and 4, the coin control
mechanism comprises; a supporting panel or
plate 18 which is fixedly mounted in the ma-
chine casing; a coin detecting mechanism car-
ried by the plate 18 and indicated generally
by the numeral 19; an operating shaft 21 70
journaled in the plate 18; and a control
handle 22 for turning the shaft 21.

The supporting plate 18 is rectangular in
shape and is attached by means of screws
23 to a brace plate 24 which in turn is se-
cured by bolts 25 to the side walls of the ma-
chine casing. The detecting mechanism 19
and the control handle 22 are exposed to the
operator through an opening 26 in the cover 75
plate 15. The cover plate 15 also includes a
coin slot plate 27 through which coins are
introduced, and a window 28 through which
the coin previously used in the operation
of the machine may be seen. 80

Referring now to Figs. 4 and 6, the coin 85
detecting mechanism 19 includes a carrier
plate or disc 29 positioned adjacent the sup-
porting plate 18, a clutch arm 31 releasably
connecting the disc 29 with the control handle
22, and an inverted cup-shaped housing 32 90
secured by bolts 33 to the plate 18. The disc
29 is mounted on a hub 34 carried by the oper-
ating shaft member 21. The control handle
22 is loosely mounted on the operating shaft
member 21, being connected thereto through 95
the clutch arm 31, the carrier plate 29, and
the hub 34. One end of the clutch arm 31
is pivotally connected at 35 to the disc 29,
the opposite end being yieldingly connected to
said disc through a coil spring 36 which urges

the arm inwardly against the hub portion of the control handle 22. A cam lug 37 carried by the arm 31 engages in one or the other of a pair of diagonally disposed notches 38 in the hub of the handle 22. Normally the disc 29 and operating shaft 21 turn with the control handle 22. If, however, an excessive force is applied to the handle 22 in an effort to force an improper coin through the mechanism, the cam lug 37 will ride up out of one of the notches 38, as shown by the dotted lines in Fig. 5, and release the control handle from the disc 29 and the shaft 21, thereby preventing breaking of the parts due to excessive strain. A stop pin 30, positioned to engage the free end of the arm 31, limits the inward movement of said arm under the action of spring 36.

The carrier plate 29 is designed to transpose a coin introduced through the coin slot plate 27 through a series of devices which combinedly serve to check the quality of the coin as to size, shape, and material. Referring particularly to Figs. 3 and 4, the inner face of the disc or carrier plate 29 is recessed to provide a circumferential notch or pocket 39 which in the normal or inoperative position of the handle 22 is opposite the coin slot plate 27. This recess is of such diameter and thickness as to prevent the introduction of a coin which is either too thick or too large. If the coin is of such dimensions as to not pass into the pocket 39, it may be removed by the operator. The recess 39 is provided with a continuation 41 which is of considerably less depth than the main portion of the pocket and the purpose of which will be presently explained. Assuming that a coin or check has been introduced into the pocket 39, upon the turning of the handle 22 in a clockwise direction, viewing Fig. 4, which in the embodiment shown is the operating direction for shaft 21, the coin 42 is first moved to a station for detecting perforations.

The mechanism for detecting perforations in the coins or checks is best shown in Figs. 3, 6, and 7. It consists of a pawl 43 pivotally mounted on a cleat 44 which is secured by screws 45 to the inner face of the supporting plate 18. The pawl 43 projects through an aperture 46 in the plate 18, the outer end being held against the inner face of the disc 29 by a spring clip 47. If instead of using a proper coin an apertured slug is employed, the free end of the pawl 43 will be thrust into the aperture in the slug as the latter moves with the disc 29 into position opposite the free end of said pawl, thus obstructing further advance movement of the carrier 29. If a proper coin is used the pawl 43 will ride over the face of the coin allowing it to pass unobstructed. Movement of the carrier 29 in the reverse direction will return the perforated slug to the position opposite the coin

slot plate 27 from which position it may be removed by the operator.

After passing the pawl 43 the coin 42 proceeds to a small-coin detecting station which rejects undersize coins. In the embodiment shown the mechanism employed for this purpose includes a lever 48, fulcrumed at 49 on the inner face of the supporting plate 18, and a latch arm 51 pivoted at 52 on the inner face of plate 18. The short arm of lever 48 is provided with a lug 53 which projects outwardly adjacent the periphery of disc 29 through an opening 54 in the plate 18. The other arm of the lever 48 carries a bracket lug 55 which engages a set screw 56 carried by the latch arm 51. The arm 51 also is provided adjacent the periphery of disc 29 with a stop lug 57 which projects outwardly through an opening 58 in the supporting plate 18. A lock nut 59 carried by the screw 56 provides means for adjusting the relative position of the lever 48 and the latch arm 51.

When a coin of proper diameter moves in pocket 39 opposite the lug 53 it will engage the latter to pivot the lever 48 in a clockwise direction, viewing Fig. 3, which in turn pivots the latch arm 51 in a counter-clockwise direction to remove the stop lug 57 outwardly or away from the periphery of disc 29. The stop lug 57 is thus removed from the path of a shoulder 61 formed on the periphery of the disc 29, leaving said disc free to allow further advance movement or turning of the operating shaft 21. If the coin is undersize it will not engage the lug 53 and further rotation of the coin disc 29 is obstructed by engagement of the shoulder 61 with stop lug 57. By turning the operating handle 22 in the reverse direction the small coin may be carried back to the receiving position opposite the coin slot plate 27 where it may be removed by the operator.

It is very important to provide mechanism of this class with means for positively preventing operation of the controlled machine with iron checks or slugs. This is accomplished according to my invention, by providing means for preventing operation of the machine in such a manner that an iron slug can be thrown past the pole pieces of a detecting magnet such as is commonly employed for this purpose. This means, which is best shown in Figs. 4 and 5, is so designed that it will function regardless of the speed at which the mechanism is operated.

Assuming the coin 42 has passed the two stations just described, it is then carried by the disc 29 over the pole pieces 62 of a detecting magnet 63 which is secured by screws 64 to the inner face of the supporting plate 18. The pole pieces 62 are positioned in an opening 65 formed in the plate 18 and are approximately flush with the outer face of said plate. A pin 66 is positioned on the plate 18 near the periphery of disc 29 below the

pole pieces 62 and slightly in advance thereof.

The purpose of the pin 66 is to retard the movement of the coin or slug as it passes over the pole pieces 62 to give an opportunity for the magnet to catch magnetic slugs. This pin is so positioned that when the pocket 39 with the coin or slug therein arrives over the pole pieces 62 the lower edge of said coin or slug engages said pin and is temporarily checked against further movement. If the slug is magnetic it is retained in the pocket 39 by the pole pieces 62 and positively prevents any further advance movement of the carrier inasmuch as it becomes wedged between the rear edge of the pocket 39 and the pin 66. This construction positively prevents throwing of a slug past the detecting magnet, the pin 66 always controlling the movement of the coin or slug in such a way as to give the magnet opportunity to act. In some coin devices it is possible to throw an iron slug past the magnetic detecting station by operating the mechanism so rapidly that the magnet does not have a chance to catch and hold the slug. Iron slugs retained in the pocket 39 may be removed by turning the carrier back to the original receiving position opposite coin slot plate 27.

If the coin 42 is non-magnetic it is only temporarily retained over the pole pieces 62 by the pin 66, thereafter dropping part way from the pocket 39 and falling between the pin 66 and a lug 67 which projects through an aperture 68 in the plate 18.

The lug 67 is carried by the short arm of a lever 69 which is fulcrumed at 71 to the inner face of supporting plate 18. The long arm of lever 69 carries a lug 72 which extends outwardly through an aperture 73 in the plate 18, and a second lug 74 which projects inwardly to engage an arm 75 of a trip lever 76, the latter being pivoted at 77 to the inner face of plate 18. The trip lever 76 is provided with a second arm 78 which extends upwardly to engage a projection 79 on the latch arm 51.

The action of the coin 42 in passing between the stop pin 66 and lug 67 is best shown in Fig. 5. As the coin falls part way out of the pocket 39 it clears the rear edge of said pocket and is then forced downwardly by the continuation 41 of the pocket 39. This downward movement of the coin between the pin 66 and the lug 67 pivots the lever 69 in a counter-clockwise direction, viewing Fig. 3. This movement of the lever 69 raises the lug 72 to release a previously used coin 81 which has been held between the lug 72 and the pointed end 82 of a plate member 83 carried by the supporting plate 18. It will be observed that the continuation 41 extends a considerable distance around the periphery of carrier plate 29, and gradually tapers toward the outer edge of said plate. The coin is thus gradually forced between pin 66 and

lug 67, thereby giving plenty of time for release of the previously used coin.

When supported between the lug 72 and the point 82 the previously used coin 81 is visible through the window 28 in the cover plate 15. This feature of visibility serves as an added precaution to aid the owner of the machine in detecting fraudulent operation of the machine by coins which may possibly have escaped the previously outlined tests.

Continuing the reference to Fig. 3, movement of the lever 69 in a counter-clockwise direction also pivots the trip lever 76 in a clockwise direction by engagement of the lug 74 with the arm 75. This movement of the lever 76 throws the arm 78 against the lug 79 thereby swinging the ratchet arm 51 to remove the stop lug 57 away from the disc 29, thereby avoiding engagement with a tooth 84 on the periphery of the disc 29. After the tooth 84 clears the lug 57 the plate 29 is free to be advanced through a complete revolution. After the coin 42 passes between the stop pin 66 and the lug 67 it falls to the display station between the lug 72 and the point 82 where it remains until its release by the succeeding coin. A coil spring 85 connected at one end to the plate 18 and at the other end to the latch lever 51 yieldingly holds the system of levers 48, 69, and 76 in their normal obstructing positions.

After a coin has been accepted return movement of the disc 29 is prevented by a latch arm 86, pivoted at 87 to the inner face of plate 18, and provided with a stop lug 88 projecting outwardly through an opening 89 in the plate 18. The lug 88 is positioned adjacent the periphery of the disc 29 and engages a series of ratchet teeth 91 to prevent return movement of the disc 29 after the coin has been finally accepted. A coil spring 90, extending between latch arm 86 and the trip lever 76, holds the lug 88 yieldingly against the edge of disc 29. After the acceptance of the coin, continued turning of the handle 22 carries the disc 29 forward to the initial receiving position shown in Fig. 4. When this position has been reached reverse movement is prevented by engagement between the stop lug 57 and a notch 92 formed in the periphery of the disc 29. Coins released from the holding or display station opposite the window 28 are conducted by a coin chute 93 to a coin box in the bottom of the casing.

From the foregoing description it will be apparent that the detecting mechanism progressively checks the quality of the coin before allowing it to be finally accepted. After acceptance of the coin the carrier is free to be turned through a complete revolution to operate the vending mechanism or other coin operated apparatus. Until the coin is finally accepted the carrier may be turned in the reverse direction to return the coin to the operator.

The particular connection between the shaft member 21 and the operative mechanism of the machine is determined by the type of machine to which the coin mechanism is to be applied. In the embodiment selected for illustration in the drawings the mechanism is shown as provided with connections for operating a vending machine of the type shown in my co-pending application, Serial No. 516,055, filed February 16, 1931. This connecting mechanism includes a spur gear 94, secured to the shaft 21, and a second spur gear 95, rotatably supported on a stud 96 carried by the plate 18. The gear 95 is connected to the vending mechanism through a link 97 which is eccentrically connected at 98 to the gear 95, said link being provided at its lower end with a pin 100 which connects with the vending machine.

The vending mechanism is intended to deliver a package each time the gear 95 makes a half revolution, this being effected by a complete revolution of the gear 94. An aligning lever 99 pivoted at 101 to the plate 18, engages a diagonally disposed pair of studs 102 carried on the outer face of gear 95. A coil spring 103, connected at one end to the free end of the lever 99 and at the other end to the plate 18, yieldingly holds said lever against the studs 102.

It will be understood that the coin mechanism may be used for the purpose of merely introducing coins into a coin-operated machine, in which case it would not be necessary to use connecting means for driving the mechanism from the shaft 21.

The control mechanism combines in a single unitary structure all of the necessary means for effectively checking the quality of a coin. The entire structure may be assembled as a unit which may be readily applied to any desired type of coin-operated machine. This feature tends to greatly increase the marketability of the article and is an important sales factor.

While I have referred in the description of the invention to the application of the mechanism to coin-operated machines, it will be understood that machines which are operated by checks rather than coins are to be considered as within the class of coin-operated machines as contemplated by the invention.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. Coin mechanism comprising, a coin carrier adapted to be moved from an initial coin-receiving position to a coin-discharging position, a detecting magnet disposed adjacent the path of movement of said carrier, and

means for retaining a coin or slug contained in said carrier within the sphere of action of said magnet, whereby to insure detection and retention of the same if it be a magnetic slug, said means in such event also preventing further movement of the carrier. 70

2. Coin mechanism comprising, a coin carrier adapted to be moved from an initial coin-receiving position to a coin-discharging position, a detecting magnet disposed adjacent 75 the path of movement of said carrier, and means for retaining a coin or slug contained in said carrier within the sphere of action of said magnet, whereby to insure detection and retention of the same if it be a magnetic slug, said means in such event also preventing further movement of the carrier but permitting such movement if the carrier contain a proper coin which is not retained by said magnet. 80

3. Coin mechanism comprising, a coin carrier adapted to be moved from an initial coin-receiving position to a coin-discharging position, a detecting magnet disposed adjacent 85 the path of movement of said carrier, and means for detaining a coin or slug contained in said carrier within the sphere of action of said magnet, whereby to insure detection and retention of the same if it be a magnetic slug, said means comprising a stop member 90 positioned to engage such coin or slug as it moves opposite the magnet, said member positively engaging a slug retained in the carrier to prevent further movement of the latter. 95

4. Coin mechanism comprising, a rotary carrier adapted to be turned from an initial coin-receiving position to a coin-discharging position, a detecting magnet disposed adjacent 100 the path of movement of the carrier, and means for detaining a coin or slug contained in said carrier within the sphere of action of said magnet whereby to insure detection and retention of the same if it be a magnetic slug, said means in such event also preventing further movement of the carrier. 105

5. Coin mechanism comprising, a rotary carrier adapted to be turned from an initial coin-receiving position to a coin-discharging position, a detecting magnet disposed adjacent 110 the path of movement of the carrier, and means for detaining a coin or slug contained in said carrier within the sphere of action of said magnet, whereby to insure detection and retention of the same if it be a magnetic slug, said means comprising a stop member 115 positioned to engage such coin or slug as it moves opposite the magnet, said member positively engaging a slug retained in the carrier to prevent further movement of the latter. 120

6. Coin mechanism comprising, a carrier 125 adapted to be moved from an initial coin-receiving position to a coin-discharging position, and means for checking the quality of the coin during said interval of movement of the carrier, said means including a device 130

for detecting perforated coins, a device for detecting undersize coins, and means for detecting magnetic slugs, said last-mentioned means including a magnet disposed adjacent the path of movement of the carrier, and means for detaining a coin or slug contained in said carrier within the sphere of action of said magnet, whereby to insure detection and retention of the same if it be a magnetic slug, said means in such event also preventing further movement of the carrier.

7. Coin mechanism comprising, a plate, a carrier rotatably supported on said plate, said carrier being provided with a circumferential recess affording a pocket for receiving and holding a coin against the plate during a portion of a revolution of the carrier thereon, an operating handle for turning said carrier, and means for checking the quality of the coin during the progress of its movement about the axis of said carrier, said means including a magnet disposed adjacent the path of movement of the carrier, and means for detaining a coin or slug contained in said recess within the sphere of action of said magnet, whereby to insure detection and retention of the same if it be a magnetic slug, said means in such event also preventing further movement of the carrier.

8. Coin mechanism comprising, a plate, a carrier rotatably supported on said plate, said carrier being provided with a circumferential recess affording a pocket for receiving and holding a coin against the plate during a portion of a revolution of the carrier thereon, an operating handle for turning said carrier, and means for checking the quality of the coin during the progress of its movement about the axis of said carrier, said means including a magnet disposed adjacent the path of movement of the carrier, and means for detaining a coin or slug contained in said recess within the sphere of action of said magnet, whereby to insure detection and retention of the same if it be a magnetic slug, said means comprising a pin disposed adjacent the periphery of the carrier, said pin being positioned to engage such coin or slug as it moves opposite the magnet, said pin positively engaging a slug retained in said recess in the carrier to prevent further movement of the latter.

9. Coin mechanism comprising, a carrier adapted to be moved from an initial coin-receiving position to a coin-discharging position, means for checking the quality of the coin during said interval of movement of the carrier, said means including a magnet disposed adjacent the path of movement of the carrier, means for detaining a coin or slug contained in the carrier within the sphere of action of said magnet, whereby to insure detection and retention of the same if it be a magnetic slug, said means in such event also preventing further movement of the carrier,

and means for holding and displaying the previously introduced coin during the interval between successive coin actuations of the mechanism.

10. Coin mechanism comprising, a carrier 70 adapted to be moved from an initial coin-receiving position to a coin-discharging position, means for checking the quality of the coin during said interval of movement of the carrier, said means including a magnet disposed adjacent the path of movement of the carrier, means for detaining a coin or slug contained in the carrier within the sphere of action of said magnet, whereby to insure detection and retention of the same if it be a 75 magnetic slug, said means in such event also preventing further movement of the carrier, and means for holding and displaying the previously introduced coin during the interval between successive coin actuations of the 80 mechanism, said means being operated by the succeeding coin to release the coin on display.

In witness whereof I hereunto subscribe my name to this specification. 85
